UNITED STATES PATENT OFFICE.

OLAF R. OLSEN AND HARMON H. FULTON, OF INDIANAPOLIS, INDIANA,
ASSIGNORS TO ELIJAH B. MARTINDALE, OF SAME PLACE.

PULLEY.

SPECIFICATION forming part of Letters Patent No. 271,108, dated January 23, 1883.

Application filed August 7, 1882. (No model.)

To all whom it may concern:

Be it known that we, OLAF R. OLSEN and HARMON H. FULTON, of the city of Indianapolis, county of Marion, and State of Indiana, 5 have invented certain new and useful Improvements in Wheels or Pulleys, of which the following is a specification.

Our said invention consists in certain improvements in the construction of that class of 10 pulleys or wheels which are pressed from pulp, paper, or other compressible material, as will be hereinafter more specifically described.

Referring to the accompanying drawings, which are made a part hereof, and on which 15 similar letters of reference indicate similar parts, Figure 1 is a side elevation of a pulley embodying our said invention; Fig. 2, a central vertical section of the same on the dotted line xx ; Fig. 3, an inside elevation of one-half the hub of our improved pulley, and Fig. 20 4 a side elevation of a pulley, the hub whereof has flanges of a different form.

In said drawings the portions marked A represent the web and rim of the pulley; B, 25 the hub, and C the shaft.

The web and rim A is constructed by being pressed from pulp, paper, or other compressible material. This in itself, however, forms no part of our invention, as we are aware that a pulley 30 formed from pulp has been patented. Depressions a are formed in the web during the process of pressing the same to receive corresponding projections on the hubs, whereby said web is prevented from turning on said hubs.

The hubs B are formed in two parts, one on each side, and are connected by bolts b^2 . Each part has a projection, b , on its inner face, which

fits into the recesses or depressions a in the web. These projections are preferably square, 40 as shown in Fig. 3, so as to prevent the web from turning thereon, and are intended to wedge tightly into said depressions, so as to hold the parts firmly in unvarying relation. It will be readily seen that by our construction 45 the hubs can be readily removed and replaced, and in case it is desired to use the pulley on a different-sized shaft it can be done by removing one hub and substituting another.

The form of flanges shown in Fig. 4 is intended more especially for the larger-sized pulleys, the common round flanges shown in the other figures being preferable for small and medium sizes.

Having thus fully described our said invention, what we claim as new, and desire to secure by Letters Patent, is—

1. The combination, with a pulley web and rim A, pressed from pulp, paper, or other compressible material, of flanged hubs B, said hubs 60 being bolted to said web by bolts b^2 , substantially as set forth.

2. The combination, with the pulley web and rim A, pressed from pulp, paper, or other compressible material, and having depressions a 65 therein, of hubs B, having projections corresponding to said depressions, and adapted to enter the same, substantially as set forth.

In witness whereof we have hereunto set our hands and seals, at Indianapolis, Indiana, this 70 3d day of August, A. D. 1882.

OLAF R. OLSEN. [L. S.]
HARMON H. FULTON. [L. S.]

In presence of—

C. BRADFORD,
E. W. BRADFORD.
